UNITED STATES PATENT OFFICE.

JAMES A. MOXEY, OF CHICAGO, ILLINOIS, ASSIGNOR, BY MESNE ASSIGNMENTS, TO
INTERNATIONAL HARVESTER COMPANY, A CORPORATION OF NEW JERSEY.

FOLDING END-GATE.

1,308,189.

Specification of Letters Patent.

Patented July 1, 1919.

Application filed May 17, 1915. Serial No. 28,603.

To all whom it may concern:

Be it known that I, JAMES A. MOXEY, a citizen of the United States, residing at Chicago, in the county of Cook and State of Illinois, have invented certain new and useful Improvements in Folding End-Gates, of which the following is a full, clear, and exact specification.

My invention relates to folding end-gates for wagon beds, and has for its object to simplify and improve the operation and construction of the means employed for supporting the same in operative position.

In folding end-gates heretofore in general use a wooden bar has been employed for supporting the end-gate in position within the wagon bed. Such a bar I have found is, under heavy strains, susceptible of breakage, and users of these forms of end-gates have long felt the need of a more substantial supporting member which, while not adding to the weight of the end-gate, will serve securely to hold it in proper position under all conditions. The substitution 25 of a metal bar for the wooden bar heretofore used is, of course, the practical solution of these difficulties; but such a bar should be of spring metal and have a free movement in an in and out direction in order to insure its locking engagement when the end-gate becomes warped.

A locking means must be provided for this bar which will positively hold it securely against disengagement. The friction locking devices now in use are unsuited for this purpose owing to the bending or flexing of the spring metal bar when great pressure is applied to the end-gate from within, the consequence of which would be to cause the 40 pinioned end of the bar to spring outwardly from beneath the locking device.

My invention contemplates the employment of a spring metal supporting bar for holding the hinged sections of the end-gate in extended position, and means whereby this bar may be locked in fixed position and held therein secure against any possibility of release.

One form which my invention may assume is exemplified in the following description and illustrated in the accompanying drawing, in which—

Figure 1 shows a plan view of the rear portion of a wagon bed provided with a 55 folding end-gate embodying my invention;

Fig. 2 shows a rear elevation of the end-gate shown in Fig. 1; and

Fig. 3 shows a plan view of the same end-gate in unlocked position.

Referring more in detail to the accompanying drawing, there is shown a wagon bed 10 provided with vertical cleats 11 to receive the hinged members 12 of the folding end-gate. Four cleats 13, vertically arranged, are provided on the exterior surface of the end-gate, and a spring metal bar 14 extending the full length of the end-gate is secured to the cleats 13 on one of the hinged members by means of bolts 15. On the outer cleat 13 of the other hinged member is pivoted, by means of a bolt 16, a segmental locking member 17 provided with an operating handle 18. The free end of the bar 14, it will be seen, terminates adjacent to the outer cleat, and the locking member 17 thereon is so positioned that when its straight edged portion 19 is presented toward the supporting bar no engagement will be effected between those parts; whereas, when the arcuate portion 20 is presented toward the bar, an overlapping engagement will be effected sufficient to hold said bar and adjacent hinged member against relative movement. The handle 18 is so positioned upon the locking member that when the straight edged portion is turned toward the bar said handle will be in its upper position of movement, and when the arcuate portion is turned toward the bar the handle will be pointed downwardly.

The cleats 13, it will be seen, are all of the same thickness, and therefore I have provided an inwardly directed offset portion 21 on the free end of the supporting bar in order to effect a more perfect connection between the locking member and the bar. This, of course, is not essential, and where employed the extent of offset depends upon the resilient quality of the metal bar. To prevent the bar 14 from moving inwardly 100 too far and thus becoming disengaged from the locking member, thereby permitting the locking member to swing about its pivot, I have provided a short cleat 22 on the end-gate adjacent to the free end of the bar and so arranged as to have its outer surface engaged by the bar when in locked position.

It is a well-known fact that a wooden end-gate often becomes warped, and the hinges thereon shrink in such a way that it 110

becomes impossible to completely open the hinged sections. In this contingency a supporting member capable of a wide range of adjustment is required in order to insure locking of the parts. Obviously, the spring metal bar employed in my device is capable of yielding sufficiently to effect a fitting of the parts at all times for locking purposes. Furthermore, the bar is spaced apart from the end-gate a sufficient distance to permit the operator to insert his hand between the bar and end-gate, and thus an advantageous leverage is secured which will be found convenient both in inserting and removing the end-gate.

Owing to the resilient quality of the supporting bar, which is constructed thus to insure its easy movement to locking position at all times, it is found in practice that a heavy pressure from within will tend to force the hinged members outwardly, bending the supporting bar in so doing. In extreme cases this bending or flexing of the spring metal bar is so great as to cause the locked end thereof to slip from beneath the locking member, thereby releasing the end-gate. To overcome this I have provided on the handle 18 an enlarged portion 23 having an arcuate slot 24 formed therein, and in position to enter said slot is a stud 25 fixed upon the supporting bar. With the parts in locking position, as shown in Fig. 2, the stud will be held within the slot and thereby longitudinal movement of the end of the supporting bar will be prevented and the most excessive strains on the end-gate cannot cause a bending of the resilient bar or a consequent springing out of its locked end.

While I have shown and described but one form of my device, it is to be understood, nevertheless, that it is susceptible of modification, and, therefore, changes may be resorted to in many of the details without departing from the spirit of my invention as disclosed in the appended claims.

What I claim as new, and desire to secure by Letters Patent, is:

1. In a folding end-gate, a pair of hinged sections, a supporting member having a substantially flat engaging portion secured to one of said sections extending substantially across both of said sections and having a lateral projection extending out-

wardly from the substantially flat portions 55 of said supporting member, and a locking member secured to the other section, said locking member having a portion to prevent a relative movement of the supporting member in one direction, and another portion 60 coöoperating with said projection to prevent relative movement in another direction.

2. In a folding end-gate, a pair of hinged sections, a supporting member therefor, a locking member for said supporting member, said locking member being provided with an arcuate slot, and a stud on said supporting member to coact with said slot.

3. In a folding end-gate, a pair of hinged sections, a flexible bar for supporting said 70 sections, a locking member for said bar provided with an arcuate slotted portion, and means on said bar to enter the slot.

4. In a folding end-gate, a pair of hinged sections, a spring metal bar spaced from and 75 secured to one of said sections, a locking member on the other section to engage with said bar, said locking member being provided with an arcuate slot, and a stud carried on said bar to coact with the slot.

5. In a wagon bed, vertical cleats arranged on each side of said bed near the end thereof and spaced apart, hinged end-gate sections received within said cleats, a flexible supporting member arranged on the end-gate and secured to one of the hinged members, said supporting member having a stud and a locking member on the other one of said hinged members to engage with the supporting member, said locking member 90 being provided with means to engage with the stud of said supporting member to hold it against flexing movement.

6. In a wagon bed, vertical cleats arranged on each side of the bed near the end 95 thereof and spaced apart, hinged end-gate sections received within the cleats, a flexible supporting bar having a stud and secured at one end to one of the hinged members, a locking member pivoted to the other one 100 of the hinged members in position to engage with the free end of the supporting member, a handle on said locking member provided with a slot to coöperate with the stud of said supporting bar to hold it 105 against longitudinal movement.

In testimony whereof I affix my signature.
JAMES A. MOXEY.
